(74) Attorney, Agent, or Firm — SLEMAN & LUND LLP

(57) **CLAIM**

The ornamental design for the retractable barrier device as shown and described.

DESCRIPTION

FIG. 1 is a front view of the retractable barrier device showing my new design;

FIG. 2 is a left side view thereof;

FIG. 3 is a right side view thereof;

FIG. 4 is a back view thereof;

FIG. 5 is a top plan view thereof;

FIG. 6 is a bottom plan view thereof; and,

FIG. 7 is a front perspective view thereof.

It is noted that any broken line illustrations in the drawings depict portions of the retractable barrier device and are not part of the claimed design.
